YARN-TENSION DEVICE

Application filed April 9, 1929. Serial No. 353,799.

The object of my invention is to provide certain improvements in the construction, form and arrangement of the several parts of a device for tensioning yarn, whereby the threading of the yarn through the device may be facilitated.

My invention comprises a tension device of the gravity operated tension washer type, in which the supporting frame is provided with a ring portion spanned by a spider which forms a support for the coating tension washers and their retaining pin. The supporting frame is also provided with an elongated closed loop offset from and partly surrounding the ring portion, the outer and inner walls of which loop are shaped to facilitate the threading of the yarn between said tension washers, pairs of "leading-in" and "leading-out" recesses being formed at the ends of the loop for guiding the yarn as it enters the tension device from one direction and leaves the tension device in another direction.

A practical embodiment of my invention is represented in the accompanying drawings, in which

Fig. 1 represents the tension device in top plan, the path of the yarn through the device being indicated by dotted lines;

Fig. 2 represents the tension device in side elevation;

Fig. 3 represents a front elevation of the tension device;

Fig. 4 represents a vertical central section taken in the plane of the line IV—IV of Fig. 1, looking in the direction of the arrows.

The supporting frame of the tension device is shown as removably attached to a vertical bar 1 by providing the frame with a lug 2 having an open-sided recess 3 for receiving the bar and a clamp screw 4 for securing the frame to the bar. The frame is provided with a ring portion 5 which is spanned by a spider support for the tension washers and their retaining pin. The three arms 6, 7, 8 of the spider lead to a centrally arranged vertical hollow lug 9. The tension washer retaining pin 10 uprises from this lug 9 and it is herein shown as having a reduced shank 11 forming a shoulder 12 resting on the top

of the lug, the lower end of the shank projecting beyond the bottom of the lug and threaded to receive a nut 13 for securing the pin to the lug 9.

The under tension washer 14 has a depending inner annular flange 15 surrounding the pin 10 and spaced therefrom, and a downwardly and outwardly directed peripheral flange 16 which rests upon the arms 6, 7, 8 of the spider, the upper surfaces of said arms being stepped to form seats for the said peripheral flange 16 of the under tension washer.

The upper tension washer 17 normally rests, by gravity, upon the lower tension washer 14. This upper tension washer is shown as having an uprising inner annular flange 18 surrounding and loosely fitting the washer retaining pin 10 and an upwardly and outwardly inclined peripheral flange 19 coating with the downwardly and outwardly inclined flange 16 of the lower tension washer, to facilitate the entry of the yarn between the washers.

The washer retaining pin 10 is preferably provided with an annular groove 20 located in the plane of the meeting faces of the two tension washers for receiving the yarn as it passes around the pin.

The supporting frame of the tension device is also provided with an elongated closed loop 21, offset from the ring portion 5 and partially surrounding it, the inner curved wall of the loop being the outer wall of the ring portion 5, and the outer curved wall of the loop being denoted by 22. The outer wall of the ring portion is provided with two uprising flanges 23, 24, forming guards for facilitating the threading of the yarn and for preventing the wrong threading of the yarn. These flanges provide between them a shallow top recess 25. The side portions of the outer wall 22 of the loop 21 are located above the plane of the ring portion and thread guiding recesses 26, 27 are thereby formed between them and the uprising flanges 23, 24. These side portions of the outer wall of the loop are curved down into the plane of the ring portion to form a shallow front top recess 28 and two shallow bottom recesses 29, 30, the

last named bottom recesses 29, 30, coacting with the grooves 26, 27 respectively, to guide the yarn into and out of the tension device.

In threading the yarn it is pulled upwardly through the closed loop 21 and the open loop thus formed in the yarn is passed over the pin 10 and in between the tension washers 14 and 17. As the winding of the yarn starts, it will be drawn into the shallow recess 20 of the washer retaining pin 10; the incoming portion of the yarn will be drawn along the bottoms of the recesses 26, 29, and the outgoing portion of the yarn will be drawn along the bottoms of the recesses 27 and 30. The top shallow recesses 25 and 28 in the opposite walls of the loop 21 permit the ready grasping of the yarn to pull it upwardly through the loop for threading the yarn. The uprising flanges 23 and 24 on the inner wall of the loop not only serve together with the side portions of the outer wall 22 of the loop to form the recesses 26, 27, but also serve as guards to facilitate the threading of the yarn and for preventing the yarn from being unintentionally threaded in the wrong manner through the tension device.

By the term "yarn" it is to be understood that I wish to include thread, twine or other equivalents.

It is evident that various changes may be resorted to in the construction, form and arrangement of the several parts without departing from the spirit and scope of my invention; hence, I do not wish to limit myself to the particular embodiment herein shown and described, but

What I claim is:—

1. A yarn tension device comprising tensioning means and a supporting frame therefor provided with an offset closed loop through which the yarn is drawn upwardly in loop form in the threading of the yarn through the tensioning means.

2. A yarn tension device comprising coacting tension washers and a supporting frame therefor provided with an offset closed loop through which the yarn is drawn upwardly in loop form in the threading of the yarn through the tension washers.

3. A yarn tension device comprising tensioning means and a supporting frame therefor provided with an offset closed loop through which the yarn is drawn upwardly in loop form in the threading of the yarn through the tensioning means, said supporting frame having "leading-in" and "leading-out" recesses for guiding the yarn into and out of the tensioning means.

4. A yarn tension device comprising coacting tension washers and a supporting frame therefor provided with an offset closed loop through which the yarn is drawn upwardly in loop form in the threading of the yarn through the tension washers, said supporting frame having "leading-in" and "leading-

out" recesses for guiding the yarn into and out of the tension washers.

5. A yarn tension device comprising coacting tension washers and a supporting frame therefor provided with a ring portion and an offset closed loop through which the yarn is drawn upwardly in loop form in the threading of the yarn through the tension washers, a spider spanning said ring portion and a washer retaining pin uprising from the spider.

6. A yarn tension device comprising coacting tension washers and a supporting frame therefor provided with a ring portion and an offset closed loop through which the yarn is drawn upwardly in loop form in the threading of the yarn through the tension washers, a spider spanning said ring portion and a washer retaining pin uprising from the spider, the outer wall of the ring portion and the outer wall of the loop having pairs of coacting "leading-in" and "leading-out" recesses for guiding the yarn into and out of the tension device.

7. A yarn tension device comprising coacting tension washers and a supporting frame therefor provided with a ring portion and an offset closed loop through which the yarn is drawn upwardly in loop form in the threading of the yarn through the tension washers, a spider spanning said ring portion and a washer retaining pin uprising from the spider, the outer wall of the ring portion and the outer wall of the loop having pairs of coacting "leading-in" and "leading-out" recesses for guiding the yarn into and out of the tension device, the outer wall of the ring portion also having uprising flanges forming guards for the tension washers.

8. A yarn tension device comprising coacting upper and lower tension washers and a supporting frame therefor provided with a ring portion, a spider spanning the ring portion forming a seat for the lower tension washer and a washer retaining pin uprising from the spider.

9. A yarn tension device comprising coacting upper and lower tension washers and a supporting frame therefor provided with a ring portion, a spider spanning the ring portion, the arms of the spider being stepped to form seats for the lower tension washer, and a washer retaining pin uprising from the spider.

10. A yarn tension device comprising coacting upper and lower tension washers and a supporting frame therefor provided with a ring portion, a spider spanning the ring portion forming a seat for the lower tension washer, a washer retaining pin uprising from the spider and an offset closed loop through which the yarn is drawn upwardly in loop form in the threading of the yarn through the tension washers.

11. A yarn tension device comprising co-

acting upper and lower tension washers and a supporting frame therefor provided with a ring portion, a spider spanning the ring portion, the arms of the spider being stepped to form seats for the lower tension washer, a washer retaining pin uprising from the spider and an offset closed loop through which the yarn is drawn upwardly in loop form in the threading of the yarn through the tension washers.

10 12. A yarn tension device comprising co-acting tension washers and a supporting frame therefor provided with a ring portion and an offset closed loop through which the yarn is drawn upwardly in loop form in the threading of the yarn through the tension washers, a spider spanning said ring portion and a washer retaining pin uprising from the spider, the outer wall of the ring portion and the outer wall of the loop having pairs of co-acting "leading-in" and "leading-out" recesses for guiding the yarn into and out of the tension device, the said outer walls of the ring portion and loop having top recesses for facilitating the manipulation of the yarn in threading the tension device.

In testimony that I claim the foregoing as my invention, I have signed my name this 6th day of April, 1929.

JOHN O. McKEAN.
